UNITED STATES PATENT OFFICE

RHINEHARD BOLLHEIMER, OF FORT LORAMIE, OHIO

WINDOW AWNING

Application filed May 10, 1929. Serial No. 362,063.

The invention primarily has for its object to provide a novel awning structure composed of metal sections connected telescopically to enable movement to and from extended and collapsed positions.

The invention further resides in certain novel details of construction which impart strength and rigidity to the awning sections and provide stops for the sections in either 10 extended or collapsed positions.

The invention further resides in the provision of novel means to facilitate relative movement of the sections and for guarding against creaking and scraping noises during 15 such movement.

The invention further resides in the provision of novel means to mount the awning upon a suitable support.

With these and other objects in view which 20 will more fully appear, the nature of the invention will be more clearly understood by following the description, the appended claims, and the several views illustrated in the accompanying drawings.

25 In the drawings:

Figure 1 is a vertical cross section illustrating the invention mounted in a window casing, the extended condition of the awning being shown.

30 Figure 2 is a view similar to Figure 1, the collapsed condition of the awning being shown,

Figure 3 is a vertical cross section of the window casing, the awning being shown in 35 side elevation in the collapsed condition,

Figure 4 is a face view of the parts shown in Figure 3, one side of the awning being shown in section,

Figure 5 is a detail horizontal section illustrating the pivotal mounting at one side 40 of the awning,

Figure 6 is a detail sectional perspective view of a side portion of one awning segment or section,

45 Figure 7 is a developed horizontal section taken on the line 7-7 on Figure 1,

Figure 8 is a detail section taken on the line 8-8 on Figure 1, and

50 Figure 9 is an edge view of the parts shown in Figure 8.

Like reference numerals designate corresponding parts throughout the several figures of the drawings.

In the drawings I have disclosed the invention mounted on a window casing. While 55 the invention is adapted for mounting with ease and facility in this manner, it is not limited in use to this precise mounting and other modes of hanging may be employed without transcending the scope of the invention as pointed out in the appended claims.

The window casing shown is of conventional form and includes the usual ceiling beam 1, the side walls 2 and the usual parting strips 3 and face molding 4.

60 In order to provide a convenient hanging mount for the awning, I provide a mounting flange 5 which may be secured as at 6 to the under face of the ceiling beam 1 and which includes a depending hook flange 7 the function of which will become evident as the description progresses.

65 The awning proper is composed of a plurality of rigid metal sections which are nested or telescopically arranged to swing in arcs about a pivot and preferably secured to the side walls 2 of the window casing. Each segment or section comprises a main body segment 8 arcuate in cross section and opposed triangular side walls 9 each having its 70 long straight edges converging to form an acute angle terminating in a pivot eye 10.

75 The rear edge of each side wall 9 is bent inwardly to form an angled reinforcing flange 11 and the front edge of each wall may 85 be bent inwardly as at 12 to form a groove for receiving a rattle and creaking noise eliminating gasket 13 and then outwardly upon the lateral face of the side wall in the form of a scroll 14. The scrolls 14 not only 90 serve to reinforce and render rigid the side edges, but also are so positioned as to constitute abutting stops as shown in Figures 3 and 4.

95 The rear flanges 11 may be split and bent to form bearings 15 for antifriction rollers 16 which will engage the inner faces of the walls 9 and coact with the gaskets 13 in facilitating telescopic movement and overcom- 100 ing creaking and scraping noises. The gas-

kets 13 and the rollers 16 may be used collectively or individually as desired. Figures 1 and 2 show the roller equipment alone, and Figure 6 shows a segment provided with both equipments.

The smallest or innermost section or segment has its advance or front edge bent inwardly to form an angled flange 17, and like all of the remaining segments, except 10 the largest one which is secured to the window casing, has its rear edge bent to form a V-shaped stop 18 and a riding face 19 which terminates in a scroll 20. Obviously the flange 17 and the parts 18 and 20 serve to reinforce and impart rigidity to the segment main body.

The rear edge of the said largest body is bent to form an upwardly extended hook flange 21 adapted to hook over and be supported by the mounting hook flange 7. See 20 Figures 2, 3 and 4. The flange 7 has its hook portion directed inwardly toward the window and thus effectively prevents rain from beating in over the upper edge of the awning 25 structure.

All of the mounting eyes 10 at the respective sides of the awning are secured to the respective window casing side wall by pivot screws 22, suitable spacers 23 being interposed to assure free pivoting and prevent rattling. See Figures 4 and 5.

All of the segments, except the smallest one hereinbefore referred to, have their front or advance edges bent back upon themselves as 35 at 24 for the purpose of reinforcement and also to provide V-stops 25 for engaging with the other stops 18 of the associated segments as shown in Figure 1 of the drawings to limit outward movement of the said segments.

Adjacent each end, a cord 26 may be secured at 27 to the flange 17 and then passed over a pulley 28 mounted upon any suitable fixed support. An example of such mounting is shown in Figure 1 of the drawing in which the pulley is secured to the outside face of one of the window casing parting strips. Thus by exerting a pull on the free ends of the cords, the awning may be raised 45 from the extended position shown in Figure 1 of the drawing to the collapsed or raised position shown in Figures 2 and 3.

As disclosed, the awning is provided with what might be termed a three point mounting; i. e., along the full length of its upper edge on the removable hook mounting 7, 21, and at each side on the respective pivot screw 22. By removing the screws 22 and lifting the hook 21 out of the hook 7, the awning 50 assembly may be removed from the window casing. The removal of the screws 22 also permits separation of the individual segments.

In the foregoing description, I have disclosed a strong rigid and yet collapsible

awning structure capable of being mounted and dismounted, assembled and disassembled quickly and with ease and in which the parts are so constructed and arranged that they may be moved relatively without undesirable noise. The structure also provides against rain beating in over the awning top edge or between the awning sections. 70

It will be obvious that while I have disclosed certain specific segment structures and means to mount them, various changes or modifications may be made without departing from the scope of the appended claims. 75

It is of course to be understood that the details of structure and arrangements of parts may be variously changed and modified without departing from the spirit and scope 80 of my invention.

I claim:

1. An awning composed of nested telescopic rigid metal segments each comprising a top body arcuate in cross section and substantially triangular side walls, and anti-noise gaskets between the said segments. 85

2. An awning composed of nested telescopic rigid metal segments each comprising a top body arcuate in cross section and substantially triangular side walls, anti-friction means between the said segments, and anti-noise gaskets between the said segments. 90

3. An awning composed of nested telescopic rigid metal segments each comprising a top body arcuate in cross section and substantially triangular side walls, and means to reinforce the front edges of the side walls of the segments and constituting stops to limit relative movement of the segments in a direction for collapsing the awning. 95

4. An awning composed of nested telescopic rigid metal segments each comprising a top body arcuate in cross section and substantially triangular side walls, front and rear edge reinforcing means for reinforcing the arcuate top bodies, and front and rear edge reinforcing means for reinforcing the side walls, said top body reinforcing means providing stops to limit relative movement of the segments in the opening direction. 100

5. An awning composed of nested telescopic rigid metal segments each comprising a top body arcuate in cross section and substantially triangular side walls, front and rear edge reinforcing means for reinforcing the arcuate top bodies, and front and rear edge reinforcing means for reinforcing the side walls, said top body reinforcing means providing stops to limit relative movement of the segments in the opening direction, and said side wall front edge reinforcing means providing stops to limit collapsing movement 115 of the segments. 120

6. An awning composed of nested telescopic rigid metal segments each comprising a top body arcuate in cross section and substantially triangular side walls, front and 125

rear edge reinforcing means for reinforcing the arcuate top bodies, and front and rear edge reinforcing means for reinforcing the side walls, said top body reinforcing means providing stops to limit relative movement of the segments in the opening direction, and anti-noise gaskets carried by said side wall front edge reinforcing means.

7. An awning composed of nested telescopic rigid metal segments each comprising a top body arcuate in cross section and substantially triangular side walls, front and rear edge reinforcing means for reinforcing the arcuate top bodies, and front and rear edge reinforcing means for reinforcing the side walls, said top body reinforcing means providing stops to limit relative movement of the segments in the opening direction, and anti-friction rollers carried by the side wall rear edge reinforcing means.

8. An awning composed of nested telescopic rigid metal segments each comprising a top body arcuate in cross section and substantially triangular side walls, front and rear edge reinforcing means for reinforcing the arcuate top bodies, and front and rear edge reinforcing means for reinforcing the side walls, said top body reinforcing means providing stops to limit relative movement of the segments in the opening direction, anti-noise gaskets carried by said side wall front edge reinforcing means, and anti-friction rollers carried by the side wall rear edge reinforcing means.

35 In testimony whereof I hereunto affix my signature.

RHINEHARD BOLLHEIMER.
